UNITED STATES PATENT OFFICE.

CHARLES FISHER, OF CHICAGO, ILLINOIS, ASSIGNOR OF ONE-THIRD TO ALBERT C. GRUNWALD, ONE-THIRD TO CARL E. CARLSON, AND ONE-THIRD TO FRED H. LOESCHER, ALL OF CHICAGO, ILLINOIS.

TOILET-PAPER FIXTURE.

Application filed July 10, 1922. Serial No. 573,953.

This invention relates particularly to a device adapted to the purpose of holding a roll of toilet paper; and the primary object is to provide a device of simple and improved construction which operates in an improved manner.

The invention is illustrated in its preferred embodiment in the accompanying drawing in which—

10 Fig. 1 represents an elevational view of the improved toilet paper holder, showing the device adapted for supporting two rolls of paper; Fig. 2 represents a rear elevational view of the same; Fig. 3, a horizontal 15 sectional view taken as indicated at line 3 of Fig. 1; Fig. 4, a broken vertical section taken as indicated at line 4 of Fig. 1; Fig. 5, a broken vertical section taken as indicated at line 5 of Fig. 1; and Fig. 6, a view partly 20 in section and partly in elevation of a modified form of trunnion.

While the device illustrated is shown adapted to support two rolls of paper, it will be understood that the device may be made 25 in suitable form to support a single roll of paper.

In the illustration given, A represents a supporting plate or base which is adapted to be attached to a vertical wall; B, B, represent 30 bracket-arms supported by the plate A and arranged in pairs; and B', B' represent spring-pressed bearings or trunnions mounted in the bracket-arms.

The supporting plate A preferably is 35 stamped from sheet-metal, being suitably bowed or paneled and provided with a marginal flange 1 which is adapted to bear against the wall. The plate is further provided with screw-receiving perforations 2.

40 The bracket-arms B are preferably made hollow, as shown. The standards may be drawn into the hollow form shown by suitable drawing operations. Each standard is thus provided with side walls 3 and an edge 45 wall 4.

The base plate is provided with pairs of vertical perforations 4 through which the standards are inserted from the rear. The rear ends of the standards are provided with 50 flanges 5, which bear against the rear surface of the plate A. The flanges 5 are spot-welded to the plate A. In practice, the standards B taper very slightly from their bases to their outer ends. The standards are

forced through the openings 4' which afford 55 a snug fit; and after the spot-welding operation the standards form virtually an integral part of the structure. Each standard is provided near its outer end, in its inner wall, with the perforation 6. The spring- 60 pressed trunnions, which may otherwise be called sheathable trunnions, project through the openings 6.

Each trunnion B' preferably comprises a 65 cup-shaped member provided with an end wall 7, a conical wall 7^a, and a flange 7^b. The trunnions are normally held in their projected position by means of coil springs 8. These springs are confined between the 70 hollow trunnions and the opposite side wall of the bracket. Preferably, a cup-shaped member or disk 9 is inserted between the spring and the outer wall of the bracket after the spring has been introduced. The 75 thickness of the metal of the cup 9 is such that the hollow trunnion can not be wholly forced from its socket after the assembling operation has been performed. Thus, the apparatus cannot be put out of order.

The flanges 7^b of the trunnion 7 are made 80 non-circular. In fact, the flanges 7^b are made to conform for a distance to the edge wall of the bracket-arms, as shown in Fig. 5, so that the trunnion can not turn about its 85 own axis.

C represents the usual paste-board tube or 90 roll on which the toilet paper roll C', indicated by dotted lines, is mounted. The paste-board tubes C are, in practice, made quite accurate in length and diameter. The 95 ends of the tubes receive the taper surfaces 7^a of the trunnions, the springs serving to force the trunnions into the ends of the tubes C with sufficient force to produce a desired friction between the toilet paper roll 100 and the trunnions. The tube C turns on the trunnions as the paper is withdrawn but there is sufficient friction between the trunnions and the paper roll to prevent the roll from turning too freely, thus insuring 105 economy.

The improved device is of exceedingly 110 staunch construction, presents a design of substantial and pleasing appearance, and is well adapted to its purpose. The trunnions may readily be retracted or sheathed to permit the paper roll to be inserted, after which the trunnions will be forced into the

- ends of the tube of the roll. In case the ends of the tube C should expand in service, the plunger-like trunnions will be projected further inwardly so as to maintain the desired friction. The feature of having both of the taper trunnions sheathable is a desirable one, as this facilitates the insertion of the roll of paper, inasmuch as the roll can be inserted by a straight movement.
- 10 The roll can not be removed until after the paper has been exhausted.

While the device shown is adapted to receive and support two rolls of toilet paper, it will be understood that the base plate 15 may be suitably designed to support one or any desired number of rolls of paper.

In Fig. 6, B² represents a modified form of trunnion, which may be used instead of the trunnions B'. In the modified form, 20 10 represents a cylindrical portion which enters the roll and 10^a represents a frustoconical portion adapted to give the necessary wedging effect to produce the desired friction between the roll and trunnion. This 25 form may be used to give a good support to the paper-roll without developing excessive friction.

The foregoing detailed description has been given for clearness of understanding 30 only and no unnecessary limitations should be understood therefrom.

What I regard as new, and desire to secure by Letters Patent, is:—

1. A toilet paper fixture, comprising a 35 supporting plate provided with a pair of slots, a pair of hollow sheet-metal bracket-arms having hollow base portions extending through said slots and equipped with retaining flanges engaging the rear surface 40 of said supporting plate, and spring projected trunnions extending through perforations with which the inner sidewalls of said bracket-arms are provided and having retaining flanges engaging the interior 45 surfaces of said inner sidewalls.

2. A device of the character set forth, comprising a supporting plate provided with a pair of slots, a pair of hollow bracket-arms, each comprising a drawn hollow 50 sheet-metal member having opposed large flat sides tapering from base to extremity, said sidewalls being joined by narrow top and bottom edge-walls and the inner sidewall having therethrough a guide-perforation, an inwardly dished trunnion working 55 through each guide-perforation, said trunnions having their closed ends presented towards each other, and a spring seated in the concavity of each trunnion and con-

fined between the end wall of the trunnion 60 and the opposed sidewall of the bracket-arm.

3. A device of the character set forth, comprising a supporting plate, a pair of hollow bracket-arms mounted thereon, said 65 arms having open base ends, a pair of cup-like trunnions insertable through the base ends of said hollow arms, said trunnions projecting through perforations in the inner side walls of said arms and being equipped with flanges disposed inside of said walls, and springs entered in said cup-like trunnions and confined between said trunnions and the outer walls of the bracket-arms.

4. In a device of the character set forth, a hollow bracket-arm having an enlarged open-ended base portion and having one of its side walls provided with a perforation, a trunnion insertable through said base portion and adapted to project through said 80 perforation, said trunnion having an enlargement at its base serving to prevent it from being projected wholly through said perforation, and a spring confined between said trunnion and the outer side wall of said 85 bracket-arm.

5. In a device of the character set forth, a hollow bracket-arm having an enlarged hollow base end and provided in one of its side walls with a perforation, a cup-like 90 trunnion insertable through the base end of said bracket-arm and having its cupped portion projecting through said perforation, a cupped disc insertable through the base of said hollow bracket-arm and disposed opposite the trunnion, and a spring having one end entering the cupped trunnion and the other end embracing the cupped portion of the opposed disc.

6. In a device of the character set forth, the combination of a base plate provided with an enlarged slot, a hollow taper bracket-arm insertable from the rear through said slot and having a flange disposed back of said plate, one side wall of said bracket-arm being provided with a perforation, a cup-shaped trunnion insertable through the base portion of said bracket-arm and having its cupped portion projecting through said perforation and having a retaining flange disposed in the hollow bracket-arm, and a spring confined between said trunnion and the opposite side wall of said bracket-arm, one end of said spring being entered in the cupped portion 110 of said trunnion.

CHARLES FISHER.
